METHOD OF MAKING GARMENT BAGS

Original Filed May 16, 1927

UNITED STATES PATENT OFFICE

ABRAHAM STONE AND MAX FROST, OF BROOKLYN, NEW YORK

METHOD OF MAKING GARMENT BAGS

Original application filed May 16, 1927, Serial No. 191,731. Divided and this application filed June 30, 1928. Serial No. 289,378.

This application refers to improvements in garment bag and method of making the same, and is a division of our co-pending application Serial No. 191,731, filed on the 16th 5 day of May, 1927.

Our invention relates to a method for making garment bag.

One of the objects of our invention is to provide an improved bag made of heavy 10 paper, of the "moth-proof" type used for protecting garments.

Another object of our invention is to provide a side-opening bag of this type having a closed and pleated side, and strongly reinforced edges. 15

Another object of our invention is to provide a bag of this type having four thicknesses of paper at the edges thereof.

Other objects of our invention will be set 20 forth in the following description and drawings, it being understood that the above general statement of the objects of our invention is intended to generally explain the same and not to limit it in any manner.

Fig. 1 is a perspective view of the blank utilized for making the bag, before the pleats have been formed at one side thereof, these 25 pleats being illustrated in Fig. 7.

Fig. 2 is a bottom view of the blank after 30 it has been cut.

Fig. 3 shows the blank shown in Fig. 1, after the glue has been applied.

Fig. 4 shows the blank illustrated in Fig. 3 after the edges have been turned.

Fig. 5 shows the blank illustrated in Fig. 4 after the intermediate score lines have been formed.

Fig. 6 is a section on the line 6—6 of Fig. 5.

Fig. 7 is a partial perspective view showing the blank after the pleat has been formed in one side thereof.

The blank B has a top 260, a bottom 261, an open side, and a closed side which may be pleated to provide having two additional layers of paper, so that the blank includes four layers of paper at the pleated side. This blank is open at one side and at the edges thereof.

The first operation according to our method is to cut a rectangular strip from the bot-

tom 261 and from the two extra layers of the closed side, leaving the top 260 uncut. This is done at both edges of the blank B, so that the edges of the bottom 261 are defined by the lines 263. Score lines 262 are also formed in the layers of the blank B, said score lines being intermediate the edge lines 263 of the narrowest portion of the blank. 55

The exposed portions of the top 260 and the edge portions of the bottom 261 are covered 60 with any suitable adhesive, which extends up to the score lines 262.

Then, as shown in Fig. 6, the edges of the blank, including all four layers thereof at the closed side, are bent over on the score lines 65 262, to secure the folded-over edges of the blank to the shortest layer thereof, as shown in Fig. 6. The completed bag has very strong reinforced edges, consisting of four layers 70 of paper. The blank is also provided with intermediate score lines 265 in the body thereof, so that it can be readily folded. The blank comprises two layers of paper, save at its closed pleated side. Hence, when the blank has been folded and pasted down, the 75 closed side has eight layers of paper, and the remainder of the blank, as illustrated in Fig. 6, has four layers of paper. The open edges of the blank can be closed in any suitable manner to complete the bag. 80

We have described a preferred embodiment of our invention, but it is clear that numerous changes and omissions could be made without departing from its spirit. 85

We claim:

1. A method of making a garment bag which consists in forming a paper blank having outer faces and a closed plaited side comprising a plurality of additional intermediate layers of paper, said blank being open at the edges thereof and at the other side thereof, then cutting strips from one of said faces and from said intermediate layers of paper at the edges of the blank so that the uncut face projects beyond the cut face and said intermediate layers, applying adhesive to the exposed edges of said uncut face on the side adjacent the cut face, and also applying adhesive to the edges of the cut face, and then folding over all the layers of the blank on 95 100

lines intermediate the edges of the cut face, and securing said folded-over edges to the cut face.

2. A method of making a garment bag which consists in forming a paper blank having end faces and a closed plaited side comprising a plurality of additional intermediate layers of paper, said blank being open at the edges thereof and at the other side thereof, then cutting strips from one of said faces and from said intermediate layers of paper at the edges of the blank so that the uncut face projects beyond the cut face and said intermediate layers, folding over all the layers of the blank on lines intermediate the edges of the cut face, and securing the folded-over layers in position.

3. A method of making a garment bag which consists in forming a blank with outer faces of unequal length, said faces being connected at one side by a closed plait comprising a plurality of additional intermediate layers of paper, said intermediate additional layers of paper having a length shorter than the length of the longer face, and folding over the edge portions of the blank on lines intermediate the edges of the shorter face, and connecting said folded-over edges to the shorter face of the blank.

30 In testimony whereof we affix our signatures.

ABRAHAM STONE.
MAX FROST.
